UNITED STATES PATENT OFFICE.

DANIEL J. HAFFORD, OF CLEVELAND, OHIO, ASSIGNOR TO THE CLEVELAND ROCK DRILL COMPANY, OF CLEVELAND, OHIO.

STEEL RETAINER.

Application filed December 18, 1922. Serial No. 607,567.

To all whom it may concern:

Be it known that I, DANIEL J. HAFFORD, a citizen of the United States, residing at Cleveland, in the county of Cuyahoga and 5 State of Ohio, have invented new and useful Improvements in Steel Retainers, of which the following is a specification.

The present invention is directed to improvements in steel retainers for rock drills 10 of the hammer type.

The primary object of the invention is to provide a device of this character so constructed that it can be easily and quickly manipulated to be moved to its operative or 15 inoperative position as the occasion may require, and will be maintained firmly in its operative position during the operation of the drill to limit the outward movement of the drill steel when not striking its work.

20 A further object of the invention is to provide a device of this nature so constructed that it will remain positively in its closed position during operation of the drill, to limit the outward movement of the steel, or 25 will firmly engage the steel to cause the same to move with the drill when it is desired to withdraw the steel from the hole being drilled.

A still further object of the invention is 30 to provide novel means to permit the steel engaging yoke to yield longitudinally of the drill so as to eliminate the possibility of the retainer yoke breaking under the blows of the steel when not striking its work.

35 With these and other objects in view, as will appear as the description proceeds, the invention accordingly consists in the novel features of construction, combination of elements and arrangements of parts herein- 40 after to be fully described and to have the scope thereof pointed out in the appended claims. In the accompanying drawing, forming a part of the specification, and in which similar characters of reference denote 45 like and corresponding parts throughout the several views thereof:

Figure 1 is a top plan view of the device.

Figure 2 is a side elevation thereof.

Figure 3 is a side elevation, showing the 50 retainer in its open or inoperative position.

Referring to the drawing, 1 designates the front head of a drill, and formed integral with the opposite sides thereof are outwardly extending diametrically disposed lugs 2, 55 the forward sides of which are rounded, as

at 3, while the rear sides are formed with flat faces 4, the purpose of which will appear later.

The retainer as a whole comprises a pair of side arms 5, the forward ends of which are turned inwardly and are integrally connected with the yoke 6, whereby said arms are so spaced as to span the front head 1 in a longitudinal direction. The rear ends of the arms 5 have formed integral therewith 60 transversely disposed heads 7 in which are formed semi-circular seats 8, which are engaged with the round sides of the lugs 2 and rotate thereon in an obvious manner.

The heads 7 have their ends provided with 70 bores 9 for slidably receiving the rear ends of the side rods 10 of the U-bolt 11, said rods being bent outwardly so that their bight portions 12 are positioned exteriorly 75 of the side arms 5 of the retainer. The plates 13 are provided and have their ends formed with circular seats 14 having perforations 15 therein for detachable engagement with the arms 10 of the U-bolts 11. The seats 14 are located adjacent the 80 extremities of the bight portions 12 of the U-bolts. These seats are engaged by the outer terminals of the coil springs 16 which encircle the side rods of the U-bolts, and have their inner terminals resting against the 85 outer surfaces of the ends of the heads 7.

A cross bar 17 is employed and has its ends provided with bores 18, which are alined with the bores 9 of the heads 7 and through which the inner ends of rods 10 of the U-bolts extend, there being nuts 19 threaded upon the extended ends thereof. These cross bars have centrally disposed blocks 20 carried thereby and with opposite sides thereof certain sides of the nuts 19 intimately engage. 90

As is well known drills of the hammer type, when running, are subjected to considerable vibration which tends to loosen the nuts 19, but owing to the fact that these nuts cannot turn due to their engagement with the blocks 20, accidental rotation, and consequent loss thereof is positively prevented. 100

Since the springs 16 are interposed between the seats 14 and heads 7 they constantly urge the U-bolts outwardly, which action causes the cross bars 17 to yieldably engage the flat faces 4 of the lugs 2, thereby holding the retainer in its operative or closed 105 110

position, and at the same time the curved seats will firmly engage the round sides 3 of said lugs.

The drill steel 21 is engaged in the front head in the usual manner, and is provided with the customary collar 22, which is of such size that it cannot pass through the yoke 6 when the retainer is in its operative or closed position, and consequently the steel 5 cannot be removed from the front head until the retainer has been moved to its open position. When this is desired the retainer is swung on an arc, or to the position as shown in Fig. 3 of the drawing, and at 10 which time the cross bars 17 will engage the round sides of the lugs 2, thereby permitting the retainer to remain in its open position until the drill steel has been changed, after 15 which upon exerting slight pressure upon 20 the retainer the seats 8 will rotate on the round sides of the lugs, and the cross bars 17 will ride from the round sides and engage the flat faces 4, thereby locking the retainer in its closed position.

While not essential, but preferable, the lugs 2 are disposed in off-set relation with respect to the longitudinal axis of the drill, which tends to cause the yoke 6 to more 25 positively engage the steel collar 22 when subjected to blows and strains.

To assemble the retainer it is first necessary to place the springs 16 under compression in any suitable manner so that the rear ends of the rods 10 are extended considerable 30 distance beyond the bars 17, after which the nuts 19 are engaged thereon, and the springs released, whereupon the rods will be drawn forwardly through the heads 7, and the nuts will then engage the sides of the 35 blocks 20, as will be obvious.

The front head 1 is further provided upon opposite sides with recesses 23 which serve as seats for the side arms 5, and serve in conjunction with the cross bars 17 addi-

tional means for holding the retainer in its 45 operative position, and against unintentional displacement. The inherent resiliency of the side arms will readily permit the same to snap into and out of engagement with said recesses. 50

What is claimed is:

1. In combination with a drill, a drill steel having a collar and operatively engaged with the drill, a pair of lugs carried by the drill, a steel retainer pivotally engaged with the lugs and comprising a collar engaging yoke, said yoke having side arms, U-bolts slidably engaged with the side arms, cross bars carried by the U-bolts, and having blocks thereon, nuts on the rods of the 60 U-bolts and engaged with the sides of the blocks, and means for holding the cross bars and side arms yieldably engaged with the lugs.

2. In combination with a drill, a drill steel 65 having a collar and operatively engaged with the drill, a pair of lugs carried by the drill, a steel retainer comprising a collar engaging yoke and having its side arms provided with heads for pivotally engaging the 70 lugs, U-bolts having their side rods extended through the heads and slidably engaged therewith, seats engaged on the rods of the U-bolts adjacent their bight portions, cross-bars engaged with the extended ends of the 75 side rods of the U-bolts and having blocks carried thereby, securing devices engaged with said extended ends and blocks to prevent accidental rotation of the securing devices, springs encircling the side rods of the 80 U-bolts and having their respective terminals engaged with the seats and heads for holding the cross bars and heads yieldably engaged with the lugs when the retainer is in its open or closed position. 85

In testimony whereof I have hereunto set my hand.

DANIEL J. HAFFORD.
